UNITED STATES PATENT OFFICE.

JOHN L. SCOTT, OF PITTSFIELD, ILLINOIS, ASSIGNOR OF ONE-HALF TO HARRY C. MILLER,
OF PITTSFIELD, ILLINOIS.

WIRE-STRETCHING TOOL,

No. 874,253.

Specification of Letters Patent.

Patented Dec. 17, 1907.

Application filed January 7, 1907. Serial No. 851,161.

To all whom it may concern:

Be it known that JOHN L. SCOTT, a citizen of the United States, residing at Pittsfield, in the county of Pike and State of Illinois, 5 have invented new and useful Improvements in Wire-Stretching Tools, of which the following is a specification.

This invention relates to wire stretching tools and has for its objects to provide a 10 comparatively simple, inexpensive device of this character which may be readily and securely engaged with the wire to be stretched, one whereby a firm grip on the wire is maintained during the stretching operation, and 15 one which will result in no injury to the wire.

With these and other objects in view, the invention comprises the novel features of construction and combination of parts more fully hereinafter described.

20 In the accompanying drawings: Figure 1 is a perspective view of a device embodying the invention. Fig. 2 is a plan view of the blank employed in forming one of the gripping members. Fig. 3 is a view of said member 25 completed. Fig. 4 is a detail cross section taken through the gripping jaws and showing the same in wire engaging position.

Referring to the drawings, it will be seen that the tool comprises a pair of crossed 30 members 1 and 2 pivotally connected at their point of intersection by means of a pintle 3 and having rearwardly extending shank portions 4 equipped with handles 5.

The member 1 is made from a blank of the 35 form shown in Fig. 2, which is bent into shape to provide a pair of spaced side portions or bearing walls 6 designed to receive between them the member 2 and a pair of forwardly projecting spaced arms 7 bent into contact at 40 their forward ends and conjointly forming an open gripping jaw 8 having a forward end wall 9 and provided on the active edges of its side portions 7 with engaging teeth or serrations 10, there being formed in that portion 45 of the blank, which is bent to produce the wall 6 perforations 11 designed to receive the pintle 3.

The member 2 is provided at its forward

end with a gripping jaw 12 of substantially V-shape in cross section having its sharpened 50 edge disposed toward the jaw 8 and adapted to enter between side portions 7 of the latter, the jaw 12 being provided on its active edge with a series of teeth or serrations 13 and terminating at its forward end in an engaging portion or finger 14, which, when the jaws are in closed position, contacts with the end wall 9 of jaw 8 to limit the closing movement of the jaws. 55

In practice, the wire to be stretched is introduced between the jaws, as in Fig. 1, after which the jaws are, by pressing the handles 4 toward each other, moved to the closed position illustrated in Fig. 4, thus causing the jaw 12 to bend the wire inward between the 60 portions 7 of jaw 8, whereby a firm grip is secured and maintained on the wire without injuring the same. When the jaws are moved to closed position the finger 14 contacts with the end wall 9 of jaw 8, as heretofore explained, to thus limit the closing 65 movement of the jaws and prevent rupturing the wire. 70

Having thus described my invention, what I claim is:

75 A device of the class described comprising a pair of cross members each consisting of a shank and a jaw, a pivot connecting the shanks at the inner ends of the jaws, and grips on the shanks, one jaw being composed 80 of a loop having its outer end curved laterally and provided with serrations at a point intermediate its ends, and the other jaw being substantially straight throughout its length and of V-shaped cross section to enter 85 the other jaw and having serrations coinciding with those of the looped jaw, and a stop on the extremity of the straight jaw which engages the laterally bent portion of the looped jaw. 90

In testimony whereof, I affix my signature in presence of two witnesses.

JOHN L. SCOTT.

Witnesses:

GEO. C. WEAVER,
HARRY C. MILLER.
